(57) **CLAIM**

We claim the ornamental design for a flexible support for an ankle brace, as shown and described.

DESCRIPTION

FIG. 1 is a perspective view of a first embodiment of a flexible support for an ankle brace according to my new design; intended for the right ankle;

FIG. 2 is a right elevation view thereof;

FIG. 3 is a front elevation view thereof;

FIG. 4 is a left elevation view thereof;

FIG. 5 is a rear elevation view thereof;

FIG. 6 is a top plan view thereof;

FIG. 7 is a bottom plan view thereof;

FIG. 8 is a perspective view of a second embodiment of a flexible support for an ankle brace; intended for the left ankle;

FIG. 9 is a left elevation view thereof;

FIG. 10 is a front elevation view thereof;

FIG. 11 is a right elevation view thereof;

FIG. 12 is a rear elevation view thereof;

FIG. 13 is a top plan view thereof; and,

FIG. 14 is a bottom plan view thereof.
